(57) **CLAIM**

The ornamental design for a delivery robot, as shown and described.

DESCRIPTION

FIG. 1 is a front right perspective view of a delivery robot showing our new design;

FIG. 2 is a rear right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

UNITED STATES PATENT AND TRADEMARK OFFICE
CERTIFICATE OF CORRECTION

PATENT NO. : D917,592 S
APPLICATION NO. : 29/706441
DATED : April 27, 2021
INVENTOR(S) : Zixun Mei et al.

Page 1 of 1

It is certified that error appears in the above-identified patent and that said Letters Patent is hereby corrected as shown below:

On the Title Page

Items (71), (72), and (73) should read as follows:

(71) Applicants: **Zixun Mei**, Edogawa-ku (JP); **Hiroyuki
Kobayashi**, Mitaka-shi (JP); **Takashi
Nishimura**, Chofu-shi (JP)

(72) Inventors: **Zixun Mei**, Edogawa-ku (JP); **Hiroyuki
Kobayashi**, Mitaka-shi (JP); **Takashi
Nishimura**, Chofu-shi (JP)

(73) Assignee: **Toyota Jidosha Kabushiki Kaisha**,
Toyota-shi, Aichi-ken (JP)

Signed and Sealed this
Twelfth Day of July, 2022
